Primary Examiner — Patricia Palasik

(57) **CLAIM**

I claim the ornamental design for the crop circle grow wheel, as shown and described.

DESCRIPTION

FIG. 1 is a front elevational view of the crop circle grow wheel, showing my new design;

FIG. 2 is a rear elevational view thereof;

FIG. 3 is a right side elevational view thereof;

FIG. 4 is a top plan view thereof;

FIG. 5 is a bottom plan view thereof; and,

FIG. 6 is a front perspective view thereof.
